UNITED STATES PATENT OFFICE.

CONSTANT FRANÇOIS MARIE GALAINE, OF RENNES, FRANCE.

OPEN-EXHAUST SILENCER.

1,076,494.

Specification of Letters Patent.

Patented Oct. 21, 1913.

Application filed January 27, 1913. Serial No. 744,505.

To all whom it may concern:

Be it known that I, CONSTANT FRANÇOIS MARIE GALAINE, a citizen of the Republic of France, and a resident of Place de la 5 Mairie, Rennes, in the Republic of France, have invented certain new and useful Improvements in Open-Exhaust Silencers, of which the following is a specification.

The present invention relates to a device 10 for a silent and open exhaust of the gases of explosive engines.

The principle of the arrangement is as follows: The exhaust tube freely open at its end is provided for one part of its length 15 with holes or narrow openings. The exhaust gases are divided into two parts, one which follows the exhaust tube and the other which traverses the openings. Consequently the pressure gradually falls in the exhaust 20 tube and a free exhaust is effected with the gradual stopping of the gases. The efficacy of the device is increased by arranging its parts in such a way as to increase the proportion of the gases which traverse the 25 openings.

The annexed drawing shows by way of example various methods of carrying out the object of the invention.

Figure 1 is a longitudinal section of a free 30 silencer; Fig. 2 is a corresponding lateral elevation seen from the left; Fig. 3 is a detail; Figs. 4 and 5 are longitudinal sections of modifications of the device.

A simple exhaust tube pierced with holes 35 or narrow openings for part of its length only gives moderate results. The proportion of gas which traverses the openings is small and in practice it is necessary to have recourse to one of the arrangements which 40 I will now describe and whose object it is to increase this proportion.

In Figs. 1 and 2, the exhaust tube *a*, which is pierced with narrow openings *a*¹ for one part of its length, is contained within a 45 tube *c* which is shorter than the tube *a*. The tubes *a*, *b*, *c*, are held at a convenient distance from one another by the end blocks *d* and also by the annular blocks *e* and *f* which act at the same time as stoppers. The 50 tube *b* is pierced with small holes *b*¹ in the part which lies between the blocks *d* and *e*.

and with relatively larger holes *b*² in the part which lies between the blocks *e* and *f*. One part of the exhaust gases has its exit directly through the tube *a*, the other part 55 traverses the openings *a*¹, then the holes *b*¹ and reenters the tube *b* through the holes *b*². The gases which go out directly through the tube *a* produce on the gases which go out from the tube *c*, that is to say, from the 60 openings *a*¹, a suction effect analogous to the action of an ejector, and they increase in consequence the proportion of gases which traverse the openings *a*¹. The efficacy of the arrangement is further increased by 65 bending back the lip *a*² of the openings *a*¹ as shown in Fig. 3.

Fig. 4 shows a modification in which the tube *b* has been replaced by two transverse stoppers *h* perforated and placed in the tube 70 *c*, which has a coned outer end *c*¹ over the outer end of the inner tube *a*, as in an ejector, so that the gases passing from the latter create a depression within the exterior tube 75 *c* to draw the gases through the lateral openings in the inner tube *a*, as indicated by the arrows.

Fig. 5 illustrates another modification which is at the same time of a simpler construction and permits of a better drawing 80 of the gases through the tube *c*. In this case, the inner tube *a* has an increased number of lateral openings *a*¹ surrounded by an intermediate perforated tube *b*. The forward end of the outer inclosing tube *c* is 85 coned over the outer end of the inner tube, as in the construction Fig. 4.

I claim as my invention:

1. A free and silent exhaust for explosive engines, comprising an interior unobstructed tube open at its outer end and having throughout a greater part of its length lateral openings, an exterior concentric tube surrounding said interior tube and means whereby the gases passing out of the end of the interior tube create a depression within the exterior tube to draw the gases through the lateral openings in said interior tube. 95

2. A free and silent exhaust for explosive engines, comprising an interior unobstructed tube open at its outer end, and having throughout a greater part of its length lat- 100

eral openings, an exterior concentric tube surrounding this interior tube, and an intermediate perforated tube, the interior and exterior tubes at their outer ends constituting an ejector to create a depression within the exterior tube to draw the gases through the openings in the interior and intermediate tubes.

In testimony whereof I have signed my name to this specification, in the presence of 10 two subscribing witnesses.

CONSTANT FRANÇOIS MARIE GALAINE.
